(57) **CLAIM**

The ornamental design for a marine display device connector, as shown and described.

DESCRIPTION

FIG. 1 is a front perspective view of a marine display device connector of the present invention;

FIG. 2 is a front view of the marine display device connector of FIG. 1;

FIG. 3 is a rear view of the marine display device connector of FIG. 1;

FIG. 4 is a right side view of the marine display device connector of FIG. 1;

FIG. 5 is a left side view of the marine display device connector of FIG. 1;

FIG. 6 is a top view of the marine display device connector of FIG. 1;

FIG. 7 is a bottom view of the marine display device connector of FIG. 1; and,

FIG. 8 is a bottom perspective view of the marine display device connector of FIG. 1 shown in a state of use.

The uneven broken lines immediately adjacent to the shaded area(s) represent the bounds of the claimed design and form no part of the claimed design. The dash-dash broken lines represent portions of the marine display device connector that form no part of the claimed design.

1 Claim, 7 Drawing Sheets
